(57) **CLAIM**

The ornamental design of a portable measurement instrument, as shown and described.

DESCRIPTION

FIG. 1 depicts a perspective view of a portable measurement instrument showing our new design.

FIG. 2 depicts a front elevation view of the portable measurement instrument.

FIG. 3 depicts a left side elevation view of the portable measurement instrument.

FIG. 4 depicts a right side elevation view of the portable measurement instrument.

FIG. 5 depicts a top plan view of the portable measurement instrument.

FIG. 6 depicts a bottom plan view of the portable measurement instrument; and,

FIG. 7 depicts a back elevation view of the portable measurement instrument.

The broken lines in the drawings illustrate unclaimed portions of the portable measurement instrument and form no part of the claimed invention.

1 Claim, 4 Drawing Sheets
